United States Patent Office

Des. 215,300

Patented Sept. 23, 1969

215,300

LOUDSPEAKER UNIT

George Bruce Kamp, Bala Cynwyd, and Stanley Rejniak, New Cumberland, Pa., assignors to International Telephone and Telegraph Corporation, a corporation of Delaware

Filed Nov. 30, 1967, Ser. No. 9,591

Term of patent 14 years

Int. Cl. D14—01

U.S. Cl. D26—14

FIG. 1 is an isometric view of the speaker unit in the vertical position showing my new design;

FIG. 2 is an isometric view of the speaker unit in the horizontal position;

FIG. 3 is a side plan view of the speaker unit; and

FIG. 4 is a front plan view of the speaker unit.

The characteristic features of my design reside in the specific arrangement of the outwardly disposed front and back portions of the loudspeaker unit.

We claim:

The ornamental design for a loudspeaker unit, as shown and described.
